GIOVANNI LOMBARDI, OF DERBY, CONNECTICUT.

MACHINE FOR MAKING SPIRAL TUBING.

1,096,513.

Specification of Letters Patent. Patented May 12, 1914.

Application filed January 24, 1912. Serial No. 673,194.

To all whom it may concern:

Be it known that I, GIOVANNI LOMBARDI, a citizen of the United States, residing at Derby, county of New Haven, State of Connecticut, have invented an Improvement in Machines for Making Spiral Tubing, of which the following is a specification.

This invention relates to certain new and useful improvements in machines for making flexible gas-tight metallic conduits for electric conductors, liquids and gases.

One of the objects of the invention is to provide improved means for bending a strip of metal into spirals and to propel said strip through the spiral forming mechanism.

A further object is to provide improved means for guiding a strip of metal to the shaping mechanism.

A further object is to provide means for feeding a suitable packing strip to the forming mechanism and for interlocking said strip with the edges of the metal strip.

A further object is to provide improved means for winding or reeling the flexible conduit after the same has been produced by the shaping mechanism.

A further object is to provide means for automatically controlling the speed of rotation of said winding or reeling mechanism to conform with the speed with which the conduit is formed by the forming mechanism.

A further object is to provide means for adjusting the automatic control of said winding or reeling means to conform to variations in the pitch of spirals which may be employed to make up the conduit.

A further object is to provide improved means for operating the means for feeding the metallic strip, the means for feeding the packing, the shaping mechanism, and the conduit winding or reeling means all in time, one with the other, to effect a continuous uninterrupted operation of the respective parts.

A further object is to provide means for inclosing a cable within a flexible conduit as the latter is formed, and leaving said cable free to be pulled into or out of said conduit.

The invention will be hereinafter fully set forth and particularly pointed out in the claims.

In the accompanying drawings:—Figure 1 is a top plan view illustrating a machine embodying my invention, parts being shown in section. Fig. 2 is a side elevation thereof. Fig. 3 is a detail view, partly in section, illustrating a portion of flexible tubing made by my improved machine. Figs. 4 and 5 are details illustrating portions of the winding mechanism for the completed tubing. Fig. 6 is a sectional view, on the line 6—6, Fig. 1. Fig. 7 is a sectional view on line 7—7, Fig. 1. Fig. 8 is a sectional view on line 8—8, Fig. 1. Fig. 9 is a sectional view on line 9—9, Fig. 1. Fig. 10 is a sectional view on line 10—10, Fig. 1. Fig. 11 is a detail sectional view illustrating the mandrel and shaping rollers.

Referring to the drawings, 10 designates a base plate on which is mounted a bracket 11 supporting a series of die or shaping rollers 12. Said rollers are connected up by a series of pinions and gears 13 driven from a shaft 14 which is connected through universal joints 15 with a propeller shaft 16. The shaft 16 is driven from a power shaft 17 mounted in the bracket 18 which also supports the shaft 16, said power shaft being driven from any suitable source of power through a pulley 19. On the end of shaft 16 is mounted a change speed gear 20, which through the intermediate gear 21 mounted on a hinged frame 22, engages a gear 23. Said gear 23 is keyed or otherwise secured to a shaft 24 which is also provided with a gear 25 meshing with an intermediate gear 26 mounted upon a quill shaft 27. Meshing with said intermediate gear 26 are three pinions 28 secured to, and driving shafts 29.

On one of the shafts 29 is secured a pinion 30 which through a series of gear 31, including one change gear, drives the quill shaft 27 in a direction opposite to the movement of said shaft 29 and at the same angular velocity as the conduit is formed. Mounted on one end of the shaft 27 is a change gear 32, meshing with an intermediate gear 33 carried on a stud 34 mounted in a curved slot 35 in the frame 18. The curvature of said slot is concentric with a shaft 36, allowing the intermediate gear 33 to be adjusted to mesh with the change gear 32 and still remain in proper mesh with a gear

37. The gear 37 is mounted on the hub 38 of a bevel gear 39 which runs freely on the shaft 36, but meshes with bevel pinions 40 mounted on a spider 41 retained in a brake 5 drum 42. Said drum is held under tension by any suitable means, such as the brake band 43 operated by a lever 44 from the free end of which is suspended a weight 45. Said weight may be varied to adjust the 10 resistance against the rotation of the drum. Meshing with the pinions 40 is a bevel gear 46 keyed or otherwise secured to the shaft 36. The gears 39 and 46 and the pinions 40 coöperate to form a differential gear, and it 15 will be noted that as the spider 41 is held from rotating, or its rotation retarded, the shaft 36 is rotated in a direction opposite to the direction of rotation of the gear 37. Keyed to the shaft 36 is a pinion 47 meshing 20 with a second pinion 48 connected with a frame 49 which is rotated thereby, said frame carrying a reel 50 upon which an electrical conductor or any other material 25 may be carried and around which the flexible conduit may be wound.

The shafts 29 are connected by universal joints or similar devices 51 with shafts 52 which are mounted to rotate in suitable bearings carried by a bracket 11^a secured to the 30 base plate 10. The conduit is shaped by a directing sleeve 54 having a flange 54^a at one end secured to an upright portion of the bracket 11^a, said sleeve being provided with an opening 55 in its side through which 35 the metal strip 56 is introduced. A mandrel 58 rotated by quill shaft 27 is passed through a suitable opening in bracket 11^a and also extends through the sleeve 54. Said quill shaft and mandrel 58 are hollow, and 40 the electric cable or conductor on reel 50 is passed through them. The sleeve 54 is provided with an internal helical groove corresponding to the pitch of the tubing, said groove causing said metal ribbon to follow 45 a helical path about the mandrel.

In making the hollow conduit illustrated in Fig. 3, the supply of metal ribbon 56 is carried on a reel 59, from which it passes 50 through a guide 60 to the die or shaping rollers 12. The peripheries of said rollers are formed to properly shape the metal strip with a flange 61 on one side and a groove 62 on the opposite side, said groove being constructed to receive a packing strip 63 prior 55 to passing through the last pair of die or shaping rollers 12, the last mentioned rollers acting to seal the packing strip in position and projecting slightly beyond the metal ribbon, leaving the latter free to pass 60 through the guiding member 64 into the directing sleeve 54. The die or shaping roller bracket 65 is mounted on the base plate 10 so that the angle at which the metal ribbon 56 is fed to the conduit forming mechanism,

is parallel to the spiral pitch angle of the 65 conduit, and as said angle varies with the diameter of the conduit and the width of metal ribbon, said bracket is made adjustable on the base plate to allow this relation to be maintained when different sizes of conduit are to be wound. The adjustment is accomplished through the medium of bolts 66 and slots 67. From the directing sleeve 54 the conduit passes to the seaming rollers 53 which coöperate with mandrel 58 to compress each spiral firmly on the succeeding spiral, effectually sealing the packed joint 70 between the spirals.

It will be noted that by passing the cable 75 through the mandrel the conduit, as formed, is loose on the cable, as the pressure of the rolls 53 is against the mandrel and not against the cable. Thus the latter is loose in the conduit and may be pulled into or out of the same.

The finished conduit as it is discharged 80 from the sleeve 54 is delivered to a collecting reel 70 which is carried in a frame 71 having hollow journals 72 rotating in bearings 73 and 73'. Secured to one of the journals 72 is a pinion 74 meshing with a similar pinion 75 keyed to shaft 36. Retained in the bearing 73' is a shaft 76 passed through the other journal 72, being held stationary by a set screw 78 and carrying on the inner 85 end a miter gear 79 which meshes with a similar gear 80 secured to the friction disk shaft 81, causing the latter to revolve in the direction indicated by the arrow. A friction disk 82 is secured to the outside of the shaft 100 81, and against said disk is pressed the friction wheel 83 mounted on a shaft 84 and adapted to slide along said shaft, driving the same through a key carried by the wheel 83, and an elongated keyway in the shaft 84. 105 Secured to the other end of the friction wheel shaft 84 is a worm 85 meshing with a worm wheel 86 secured to a short shaft 87 passing from the outside of the reel frame 71 to the inside of the latter and terminating in a grooved flange 88. One end of the reel 110 70 is provided with a tongue 89 projecting into the groove of flange 88, whereby rotary motion is imparted to the reel. The reel is held in position by a rod 90 secured 115 by a set screw 91 in the frame 71, the other end of said rod fitting in a hole in shaft 87. The lateral position of the friction wheel 83 relative to the center of the friction disk 82 which governs the amount of conduit taken 120 up by the reel 70, is controlled by a device which reduces the angular velocity of the said collecting reel 70 automatically as said reel increases in diameter. Said controlling device comprises arms 92 secured to and fulcrumed from a shaft 93, the outer ends of which are provided with a bar 94 which is pressed against the reel 70 and is forced out- 125

ward by the increase in diameter of said reel due to the winding of the completed conduit thereon. This outward movement of the arms 92 is transmitted through shaft 93 to a 5 lever 97, and from the latter through a connecting rod 95 that transmits the same to the friction wheel lever 96, which latter is provided with a forked end engaging the friction wheel 83. Thus it will be seen that said 10 friction wheel is gradually moved nearer to the center of the friction disk 82, and thus automatically compensates for the increase in diameter of the collecting reel 70. In order to compensate for difference in spiral 15 pitch, the relation between arms 92 and lever 96 may be adjusted by shifting said lever 97 on the shaft 93 and moving the connecting rod stud 100 nearer to or farther from the shaft 93, thus increasing or decreasing the 20 leverage as the case requires.

Between the reel 70 and the journals of the frame 71 is interposed a guiding device for distributing the finished conduit evenly on the whole length of said reel. Said guiding 25 device is illustrated as comprising a distributor 101 sliding on a guide rod 102 and reciprocated by means of a block 103 supported by the distributor and engaging right and left hand grooved spirals 104 in a shaft 30 105, said grooves intersecting one another and terminating at one of these intersections on each end of the shaft. The shaft 105 is actuated by a gear 106 secured to shaft 87 driving a gear 107 which meshes with a 35 second gear 108 mounted on an arm 109 hinged around gear 107 to allow the gear 108 to be brought into mesh with a change gear secured to the shaft 105. This construction, including the change gear, is employed 40 owing to the necessity of changing the driving ratio of shaft 105 when change is made in the diameter of the conduit.

In connection with the foregoing it will be noted that as the finished conduit is secured 45 to the collecting reel 70, which in turn is held in the frame 71, the rotating movement imparted to said frame 71 through the driving means tends to turn the same at a speed in excess of that at which the conduit 50 is made by the forming mechanism. This excessive movement is converted into a tension which co-operates with the conduit forming means by twisting said conduit through the conduit forming device, the differential 55 or equalizing gearing governing the movement of the parts and thereby eliminating any stoppage of the conduit forming functions during the operation of the machine, due to slipping of the die rollers 60 and seaming rollers on the metal ribbon forming the conduit.

The operation is as follows:—The shaft 36 is driven from the drive shaft 17 through the intermediate gearing carried by the

bracket 18, and the differential gearing actuated by the first mentioned gearing. The reel frames 49 and 71 are driven by said shaft 36 at the same speed, each set of gears 47, 75 and 48, 74 being of the same diameter. The die or shaping rollers are driven from the shaft 70 14 and the pressing rollers 53 are driven from shafts 29, all actuated from the main drive shaft 17 and in time with each other. As illustrated in the drawing, a metallic strip 56 and a packing strip 63 are fed past the 75 rollers 12 into the shaping device 54 and simultaneously therewith an electric conductor is fed into the said shaping device. As the metal strip is acted upon by the shaping device it is coiled around the electrical conductor and the edges pressed down by the rollers 53. As the completed conduit is discharged from the shaping device it is taken up by the reel 70. Said reel is automatically controlled in its operation to conform to the speed of discharge of the completed conduit, and is so mounted that as the conduit is wound thereon a tension is maintained on said conduit during the forming 80 operation. 90

Having thus explained the nature of my invention and described an operative manner of making and using the same, although without attempting to set forth all of the forms in which it may be made, or all of the 95 forms of its use, what I claim is:—

1. In a machine for forming flexible conduit, shaping mechanism comprising a bracket having an upright wall, a cylindrical sleeve having one end secured to one 100 face of said wall, the other end being free, a mandrel passed through said wall and said sleeve, means for introducing a continuous strip of metal into said sleeve through the side and at an angle to the 105 axis thereof, said sleeve being shaped to form said strip into a helical coil around said mandrel and discharge the same through the free end of the sleeve, die rollers surrounding said mandrel and co-operating therewith for compressing the overlying edges of the said strip, and shafts supporting said die rollers and also passed through said wall. 110

2. In a machine for forming flexible conduit, shaping mechanism comprising a bracket having an upright wall, a cylindrical sleeve having one end secured to one 115 face of said wall, the other end being free, a mandrel passed through said wall and said sleeve, means for introducing a continuous strip of metal into said sleeve through the side and at an angle to the axis thereof, said sleeve being shaped to form said strip into a helical coil around said 120 mandrel and discharge the same through the free end of the sleeve, die rollers surrounding said mandrel and co-operating 125

therewith for compressing the overlying edges of the said strip, shafts supporting said die rollers and also passed through said wall, and means for rotating the mandrel at 5 a velocity conforming to the speed at which the conduit is formed.

3. In a machine for forming flexible conduit, shaping mechanism comprising a bracket having an upright wall, a cylindrical sleeve having one end secured to one face of said wall, the other end being free, a mandrel passed through said wall and said sleeve, means for introducing a continuous strip of metal into said sleeve 10 through the side and at an angle to the axis thereof, said sleeve being shaped to form said strip into a helical coil around said mandrel and discharge the same through the free end of the sleeve, die rollers surrounding said mandrel and co-operating therewith for compressing the overlying edges of the said strip, shafts supporting said die rollers and also passed through said wall, a second bracket independent of said 15 shaping mechanism, and means carried by the last mentioned bracket for supplying a continuous strip of material to said shaping mechanism.

4. In a machine for making flexible conduit, the combination with means for coiling a continuous strip of metal and uniting the edges thereof to form a conduit, of a collecting reel upon which the completed conduit is wound, a supporting frame for 20 said reel, a shaft provided with means for rotating said frame, driving mechanism, a differential gearing intermediate of the driving mechanism and said shaft, whereby relative rotation of the parts is governed to create 25 a tension on the conduit as it is being formed, and means for rotating said reel within said frame.

5. In a machine for making flexible conduit, the combination with shaping mechanism comprising a sleeve, means for feeding a continuous strip of metal into said sleeve at an angle to the axis of the latter, whereby a helical coil is formed, and means for compressing the edges of said strip together, of means for forming complementary flanges on the edges of said strip as the latter is fed to the shaping mechanism, a collecting reel upon which the completed conduit is wound, a supporting frame for said 30 reel, a shaft provided with means for rotating said frame, driving mechanism, a differential gearing intermediate the driving mechanism and said shaft whereby relative movement of the parts is governed to create 35 a tension on the conduit as it is being formed, and means for rotating the reel within said frame.

6. In a machine for making flexible conduit, the combination with shaping mecha-

nism comprising a sleeve, means for feeding a continuous strip of metal into said sleeve at an angle to the axis of the latter, whereby a helical coil is formed, a mandrel within said sleeve, and means co-operating with said mandrel for compressing the edges 65 of said strip as the coil is formed, a collecting reel upon which the completed conduit is wound, a supporting frame for said reel, a shaft provided with means for rotating said frame, driving mechanism, a differential gearing intermediate the said shaft and said driving mechanism whereby relative movement of the parts is governed to create 70 a tension on the conduit as it is being formed, and means for rotating the reel 75 within said frame.

7. In a machine for forming flexible conduit, the combination with shaping mechanism comprising a sleeve, means for feeding a continuous strip of metal into said sleeve 85 at an angle to the axis of the latter, whereby a helical coil is formed, and means for compressing the edges of said strip, of a collecting reel upon which the completed conduit is wound, a supporting frame for said reel, a 90 shaft provided with means for rotating the frame, driving mechanism, a differential gearing intermediate said shaft and said driving mechanism, whereby relative movement of the parts is governed to create a 95 tension on the conduit as it is being formed, and means for rotating the reel within said frame.

8. In a machine for forming flexible conduit, the combination with shaping mechanism comprising a sleeve, means for feeding a continuous strip of metal into said sleeve at an angle to the axis of the latter, whereby a helical coil is formed, a mandrel within said sleeve, and means co-operating 100 with said mandrel for compressing the edges of said strip as the coil is formed, of a collecting reel upon which the completed conduit is wound, a supporting frame for said reel, a shaft provided with means for rotating said frame, a driving mechanism, a differential gearing intermediate the said shaft and said driving mechanism, whereby relative movement of the parts is governed to create a tension on the conduit as 105 it is being formed, and means for rotating the reel within said frame.

9. In a machine for forming flexible conduit, shaping mechanism comprising a cylindrical sleeve, a hollow mandrel arranged 120 coaxially thereof, means for introducing a continuous strip of metal into said sleeve at an angle to the axis of the latter, said sleeve being shaped to form said strip into a helical coil around said mandrel, means for 125 forming complementary flanges on the edges of said strip, means co-operating with the mandrel for compressing the complementary

flanges of said strip, a collecting reel for the finished conduit, a supporting frame for said reel, a shaft provided with means for rotating said reel frame, driving mechanism, 5 a differential gearing intermediate the driving mechanism and said shaft, whereby relative movement of the parts is governed to create a tension on the conduit as it is being formed, and means for rotating the reel 10 within said frame.

10. In a machine for forming flexible conduit, shaping mechanism comprising a cylindrical sleeve supported at one end, the other end being free, a mandrel arranged 15 axially thereof, means for introducing a continuous strip of metal into said sleeve at an angle to the axis thereof, said sleeve being shaped to form said strip into a helical coil around said mandrel and discharging the 20 same through the free end of the sleeve, die rollers surrounding said mandrel and co-operating therewith to compress the overlying edges of the strip, a collecting reel for the finished conduit, a supporting frame for 25 said reel, a shaft provided with means for rotating said reel frame, driving mechanism, differential gearing intermediate the shaft and said driving mechanism, whereby relative movement of the parts is governed to 30 create a tension on said conduit as it is being formed, and means for rotating the reel within said frame.

11. In a machine for making flexible conduit, the combination with means for coiling 35 a continuous strip of metal and uniting the edges thereof to form the conduit, of a collecting reel for the finished conduit, a supporting frame for said reel, and differential gearing constructed to rotate said reel 40 frame to create a tension on the conduit as the latter is being formed.

12. In a machine for making flexible conduit, the combination with means for coiling 45 a continuous strip of metal and uniting the edges thereof to form the conduit, of a collecting reel for the finished conduit, a rotatable frame for supporting the same, a supply reel, a rotatable frame in which said supply reel is mounted, and differential 50 gearing operatively connected with both of said frames.

13. In a machine for making flexible conduit, the combination with means for coiling 55 a continuous strip of metal and uniting the edges thereof to form the conduit, of a collecting reel for the finished conduit, a rotatable frame for supporting the same, a supply reel, a rotatable frame for supporting the supply reel, a shaft for rotating said 60 reel frames, and differential gearing controlling said shaft.

14. In a machine for making flexible conduit, the combination with means for coiling 65 a continuous strip of metal and uniting the edges thereof to form the conduit, of a collecting reel, a rotatable frame for supporting the same, a supply reel, a rotatable frame for supporting the supply reel, a shaft for rotating said reel frames, differential gearing 70 controlling said shaft, and including a brake drum, and means for braking said drum.

15. In a machine for making flexible conduit, the combination with means for coiling a continuous strip of metal and uniting the 75 edges thereof to form the conduit, of a collecting reel, a rotatable supporting frame therefor, a supply reel, a rotatable frame for supporting the supply reel, a shaft for rotating the reel frames, differential gearing 80 controlling said shaft and including a brake drum, a brake band coöperating with said drum, and a weight for actuating said brake band.

16. In a machine for making flexible conduit, the combination with means for forming a continuous strip of metal into a helical coil, means for compressing the edges of 85 said strip together, said means including a rotatable mandrel, and seaming rollers rotating in unison therewith, of a collecting reel, a frame in which said reel is mounted, and means for rotating said frame said rotating means including means for creating 90 a tension on said conduit as the latter is 95 formed.

17. In a machine for making flexible conduit, the combination with means for forming a continuous strip of metal into a helical coil, a rotatable mandrel, and seaming rollers 100 coöperating with said mandrel to unite the edges of said strip as the coil is formed, of a collecting reel, a rotatable frame in which said reel is mounted, and means operatively connected with said mandrel for 105 rotating said reel frame.

18. In a machine for making flexible conduit, the combination with means for forming a continuous strip of metal into a helical coil, a rotatable mandrel, and seaming rollers 110 coöperating with said mandrel to compress the edges of said strip together as the coil is formed, means for operating the mandrel, and means actuated by said mandrel operating means for creating a tension on 115 the conduit as the latter is formed.

19. In a machine for making flexible conduit, the combination with means for forming a continuous strip of metal into a helical coil, a rotatable mandrel, and seaming 120 rollers coöperating with said mandrel to unite the edges of said strip as the coil is formed, of a collecting reel, a supply reel, independent rotatable frames in which the respective reels are mounted, a shaft for rotating said reel frames in unison, a differential gearing for operating said shaft, and means operatively connected with said man- 125

drel for actuating said shaft through said differential gearing.

20. In a machine for making flexible conduit, the combination with means for forming a continuous strip of metal into a helical coil, a mandrel, and seaming rollers co-operating with said mandrel, of means for rotating said rollers, a shaft driven by said roller rotating means, said shaft being connected with said mandrel, and means operated by said shaft for maintaining a tension on the conduit as the latter is formed.

21. In a machine for making flexible conduit, the combination with means for forming a continuous strip of metal into a helical coil, a hollow mandrel, and seaming rollers co-operating with said mandrel, of means for rotating said rollers, a shaft for rotating said mandrel and driven by said roller-rotating means, a collecting reel, a rotatable frame for supporting the same, and means operated by said shaft for rotating said frame to maintain a tension on the conduit as the latter is formed.

25. 22. In a machine for making flexible conduit, the combination with means for forming a continuous strip of metal into a helical coil, a hollow mandrel, and seaming rollers co-operating with said mandrel, of means for rotating said rollers, a shaft for rotating said mandrel and driven by said roller-rotating means, a collecting reel, a rotatable supporting frame for said reel, a shaft for rotating said frame, a differential gearing for operating the last mentioned shaft, and means operated by said mandrel shaft for operating said differential gearing.

23. In a machine for making flexible conduit, the combination of means for forming a continuous strip of metal into a helical coil, a hollow mandrel, a shaft for driving the same, seaming rollers co-operating with said mandrel, means for rotating said rollers, said shaft being driven by said roller rotating means, a supply reel, a collecting reel, independent rotatable frames in which the respective reels are mounted, and means operated by said mandrel shaft for rotating said reel frames.

50 24. In a machine for making flexible conduit, the combination of means for forming a continuous strip of metal into a helical coil, a hollow mandrel, a shaft for driving the same, seaming rollers co-operating with said mandrel, means for rotating said rollers, said shaft being driven by said roller-rotating means, a supply reel, a collecting reel, independent rotatable frames in which the respective reels are mounted, a differential gearing for operating said reels and reel frames, and means operated by said mandrel shaft for actuating said differential gearing.

25. The combination with means for

forming metal strip into a continuous spiral 65 conduit, of a collecting reel, a reel frame, and means connected with the spiral-forming means for rotating said frame, said rotating means including means for creating a tension on the conduit as the latter is 70 formed.

26. The combination with means for forming metal strip into a continuous spiral conduit, of a collecting reel, a reel-frame, means connected with the spiral-forming 75 means for rotating said frame said rotating means including means for creating a tension on the conduit as the latter is formed, and means actuated by said frame for rotating said reel.

27. In a machine for forming flexible conduit means for forming a continuous strip of metal into a helical coil, a hollow mandrel, means co-operating with the periphery of said mandrel for compressing the edges 85 of said strip together as the coil is formed, and means for feeding a cable through said mandrel simultaneously with the formation of said conduit, whereby said cable is free to move longitudinally in said conduit. 90

28. In a machine for forming flexible conduit means for forming a continuous strip of metal into a helical coil, a hollow mandrel, seaming rolls co-operating with the periphery of said mandrel to compress the 95 edges of said strip together as the conduit is formed, and means for feeding a cable through said mandrel simultaneously with the formation of said conduit, whereby said cable is free to move longitudinally in said 100 conduit.

29. In a machine for forming flexible conduit means for forming a continuous strip of metal into a helical coil, a hollow mandrel, seaming rolls co-operating with 105 the periphery of said mandrel to compress the edges of said strip together as the conduit is formed, means for rotating said seaming rollers and said mandrel in opposite directions, and means for feeding a cable 110 through said mandrel simultaneously with the formation of said conduit, whereby said cable is free to move longitudinally in said conduit.

30. In a machine for forming flexible 115 conduit means for forming a continuous strip of metal into a helical coil, a hollow mandrel, means co-operating with the periphery of said mandrel for compressing the edges of said strip together as the coil is 120 formed, means for feeding a cable through said mandrel simultaneously with the formation of said conduit, whereby said cable is free to move longitudinally in said conduit and a collecting reel upon which the 125 finished conduit and the inclosed cable are wound.

31. In a machine for forming a flexible

conduit, means for forming a continuous strip of metal into a helical coil, a hollow mandrel, a hollow quill shaft to which one end of said mandrel is connected, means for rotating said quill shaft, means coöperating with the periphery of said mandrel to compress the edges of said strip together after the coil is formed, and means for feeding a cable through said quill shaft and mandrel

simultaneously with the formation of said 10 conduit, whereby said cable is free to move longitudinally in said conduit.

In testimony whereof I affix my signature in presence of two witnesses.

GIOVANNI LOMBARDI.
